X-RAY TUBE AND CATHODE STRUCTURE
THEREFORLouis Frederick Ehrke, Newark, N. J., assignor
to Westinghouse Lamp Company, a corporation
of Pennsylvania

Application December 1, 1933, Serial No. 700,415

3 Claims. (Cl. 250—35)

This invention relates to electric discharge devices and more particularly to cathode structures therefor. In its more specific aspect the invention is directed to an improved cathode structure for X-ray tubes.

X-ray tubes are employed in a number of different fields. They find special application in the radiographic and therapeutic fields. Because of the different quantities and character of X-rays and the shape of the X-ray beam, it has sometimes been necessary to employ different tubes for different purposes. In the dental field only low voltage X-rays are required whereas in the deep therapy field, relatively high voltage X-rays are required. In some cases, and especially in the radiographic field, it is sometimes essential that the focal spot on the anode be of a predetermined configuration and size.

The size of the focal spot is generally governed by two considerations, first the energy which the tube may safely pass and second the degree of detail or definition required in the X-ray film. The energy requirements make a large spot desirable but the necessity of fine definition in radiographic work makes a spot of very small area desirable. Therefore, the size of focal spots in X-ray tubes employed for radiographic purposes is one that is small but of such an area that it will successfully accommodate the energy input during operation without deleterious pitting of the target. Obviously, focal spots of different sizes are desirable in various classes of radiography. Some exposures such as chest, intestine and the like exposures in radiography require high energy inputs in the tube especially when the tube during operation is located a considerable distance from the body to be X-rayed.

Other exposures, such as body extremities, sinuses and the like require smaller power inputs. In the therapeutic field and especially that field generally known as deep therapy the energy input in an X-ray tube is commonly much greater than that required in the radiographic field.

Prior to my invention, it has been customary to employ a tube for heavy duty radiography purposes, another for light duty radiographic purposes and still another for deep therapy purposes so that the best results could be obtained in all cases. The use of different tubes for different purposes has necessitated either the employment of three circuits containing the different tubes or the time consuming task of tube replacements in accordance with particular de-

mands. These disadvantages have been apparent in all tubes of the line focus type where simple and rugged cathode structures having but a single slot were employed.

In order to obviate the above difficulties and to provide a simple cathode structure which may be readily manufactured and assembled, I have made the following invention. Briefly, the invention comprises a cathode structure for X-ray tubes and comprises a focusing cup having a slot in which are located a plurality of independent filaments so arranged that the tube may be employed for light duty radiographic, heavy duty radiographic and deep therapy purposes.

An object of my invention is to provide an improved cathode structure for an X-ray tube.

Another object of my invention is to provide an improved cathode structure for an X-ray tube so that the tube is adapted to be operated in a number of different fields.

Another object of my invention is to provide an X-ray tube of the line focus type and adapted to be efficiently operated for light and heavy duty radiography as well as for deep therapy purposes.

These and other objects of my invention will be readily apparent from the following description and drawing wherein,

Figure 1 represents a longitudinal cross sectional view with some of the parts in elevation of an X-ray tube embodying my invention.

Fig. 2 represents a top plan view of my improved cathode structure and support therefor.

Fig. 3 is an end view looking towards the open end of the cathode structure.

Fig. 4 represents the focal spot on the target of the X-ray tube when one filament of the cathode structure is incandescent.

Fig. 5 represents the focal spot on the target of the X-ray tube when all of the filaments of the cathode structure are incandescent.

Fig. 6 represents the focal spot on the target of the X-ray tube when only a portion of one of the filaments of the cathode structure is incandescent.

Fig. 7 represents the focal spot on the target of an X-ray tube when another portion of the filament than that referred to in Fig. 6 is incandescent.

Fig. 8 represents the focal spot on the target of an X-ray tube where both portions of the filament referred to in Figs. 6 and 7 are incandescent.

As shown in Fig. 1 the X-ray tube comprises

a dielectric vitreous envelope 10 having a re-entrant stem (not shown) at one end and a re-entrant stem 11 at its other end. Secured to said reentrant stem which is not shown is an 5 anode 12 having a target 13 in the free end thereof. The target may be composed of tungsten or other refractory material adapted to generate X-rays when it is subjected to electronic bombardment. Another reentrant tube 14 10 surrounds the anode 12. A plurality of resilient plates 15 are located between the anode 12 and sleeve 14 for supporting the anode.

According to my invention the stem 11 terminates in a cruciform pinch or press 16 having 15 a plurality of rods hermetically sealed therein. In one of said cross arms of said press and spaced from each other are sealed rods 19, 20 and 21. Sealed in said other cross arm and spaced from each other are rods 17, 18, 22 and 20 23. My improved cathode structure is mounted with the envelope 10 and supported by said rods. The improved cathode structure comprises a 25 block 24 consisting of a highly refractory member of molybdenum or the like in which member are properly positioned a plurality of independent filaments 26, 27 and 28 composed of tungsten, tantalum or the like.

The block 24, which is a focusing device, has a groove 29 extending along the entire length of 30 said block, with the sides of said groove in cross section being in the form of arcs of a circle. The bottom portion 30 of the block has a slot 31 35 extending from one end thereof to a point adjacent the other end thereof.

35 The slot 31 is rectangular in cross section and has its upper end coincident with the lower end of the groove 29 and its lower end coincident with the lower face of the bottom 30. The groove 29 and the slot 31 form a slot extending 40 to both the upper and lower faces of the block, a portion of the slot extends to two side limiting faces thereof and another portion to only one side limiting face thereof.

The thermionically active filaments 26, 27 and 45 28 are located in the block 24. Each of these filaments consists of an appropriately coiled tungsten or tantalum wire of predetermined thickness and coil diameter, with the diameter of each coil being substantially the same as that 50 of the adjacent coil throughout the length of said elements. The filament 26 extends along the length of slot in the block, with the central longitudinal axis of the filament being substantially parallel to the sides of the block 24 defining the slot 31 and located close to one of 55 said sides, but not contacting the same. The ends of the filament are short straight portions depending in the direction of the depth of the slot. The ends of said filament are respectively 60 welded or otherwise secured to the upper portion of the rod 17 whose end is close to said block 24 and to a metallic strap 32 welded to the bottom of said block 24. The filament 27 is spaced from said filament 26 and is also 65 mounted in said slot. The central longitudinal axes of the filaments 26 and 27 and the upper edge of the slot 31 are all in substantially the same plane. The depending ends of the filament 27 are respectively welded to the rod 18 and to a 70 metallic strap 33 welded to the bottom of the block 24.

The filament 28 is located in said slot 31 and between the upper and lower limits thereof. The filament 28 is so disposed in said slot that it 75 is located below the filaments 26 and 27 and

between the sides of the slot 31. The ends of the filament 28 depend downwardly and are respectively connected to the rods 19 and 20. Secured by welding to the coil at about one third length thereof from the open end of the slot 31 is a metallic strap 34 also welded to the bottom of the block 24.

5 The rod 21 is located in a recess and welded to the cross portion of the block which limits the length of the slot 31. The other two rods 22 10 and 23 are respectively located in recesses in and welded to the sides of said block near the other end thereof. These three rods 21, 22 and 23 support said focusing block 24. The rod 21 further functions as a current carrying means. The 15 cathode structure thus mounted has the mouth of the block 24 facing the anode.

A cap 40 carrying five conducting pins 41 is secured to the cathode end of the envelope. The pins or contacts are appropriately connected to the rods connected to the cathode and focusing cup. Surrounding the pinch or press 16 and secured to only the rod 21 is an inverted cup 42 for shielding the pinch from electron bombardment. In order that the ends 25 of the focal spots may be well defined and free from fanning I employ the invention as described by Norman C. Beese in his pending application Serial No. 680,013, filed July 12, 1933, and entitled "X-ray tube and cathode structure 30 thereof." For this purpose pins 43 and 44 are secured to the focusing block and located above and near the ends of the filaments.

In operation, if I desire a focal spot measuring about 4 mm in width so that body extremities may be radiographed, I energize only filament 26 or 27. When either one of these two filaments is energized, the sides of the focusing block and the other filaments in said block focus the electrons emanating from said energized filament. If a focal spot of lesser width is desired, I energize a portion of or all of the filament 28 depending upon the quantity of X-rays desired. If a great deal of energy is to be put in the tube all of the filaments may be 45 energized so that the focal spot may be long and broad so that the anode will accommodate the energy input without target pitting and fusion.

Although I have described my invention with 50 some particularity, it is to be limited only by the prior art.

What is claimed:

1. An electric device comprising an envelope, an anode and a cathode structure therein, said envelope having a reentrant stem terminating in a cruciform press, a plurality of rods sealed in the cross arms of said press and supporting said cathode structure, said cathode structure including a focusing means having a slot therein, the mouth of said slot facing said anode, three coiled filaments disposed in said focusing means, all of said filaments having their central longitudinal axes disposed along the length of one of the walls of said focusing means defining said slot, one of said filaments being located below the other two filaments.

2. An electric device, the combination of an envelope and an anode, with a cathode structure, said cathode structure including a focusing block having a slot therein, three coiled filaments mounted in said block with their central longitudinal axes substantially parallel to each other and along the length of said slot, one of said filaments being located below the other 75.

two, said other two filaments being spaced from each other for the passage of electrons from said first mentioned filament when the same is energized and to aid in focusing the electrons 5 from said first mentioned filament.

3. An X-ray tube comprising an envelope, an anode and a cathode structure therein, said cathode including a focusing block having a groove extending along the length thereof, with 10 the sides of the groove in cross section being of curvilinear form, a slot in the lower portion

of the block and having its upper edge coinciding with the lower edge of said groove, a pair of longitudinal filaments extending along the length of said block, with a portion of each of said filaments being located in said slot, said filaments being spaced from each other, a third filament located below said first two filaments and opposite the space between said first two filaments, said third filament being located entirely within said slot.

LOUIS FREDERICK EHRKE.
